(57) **CLAIM**

The ornamental design for warming garment, as shown and described.

DESCRIPTION

FIG. 1 is a front view of a warming garment showing my new design as worn;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The dashed lines, shown in the drawings, are for illustrative purposes only and form no part of the claimed design.
